SAFETY RAZOR

Joseph Muros, Belmont, Mass., assignor to Gillette Safety Razor Company, Boston, Mass., a corporation of Delaware

Application October 1, 1935, Serial No. 43,065

6 Claims. (Cl. 30—61)

This invention relates to safety razors of the type employing a sectional cap in combination with a guard or other blade-supporting member bodily movable with respect to the cap sections 5 to flex and clamp a blade in position for shaving. Examples of such razors are to be found in U. S. Patent No. 1,922,072, and in my own prior Patent No. 1,992,038.

The object of the present invention is to simplify the mechanism for swinging the cap sections to and from their closed position and for moving the blade-supporting member to flex and clamp the blade. As herein shown, the cap sections are pivotally mounted upon the handle member by 15 supporting arms and a guard is provided having notches arranged to engage arms of the cap sections and lock them in closed cap position while the blade-flexing or blade-releasing operations are being effected, that is to say, the cap sections 20 are positively locked against pivotal movement during the blade-flexing and blade-releasing movements of the guard. This insures an even and normal pressure of engagement when the blade is flexed and a straight line movement of 25 separation of the parts when the blade is released, thus avoiding damage to the cutting edge of the blade and facilitating the manipulation of the razor by the user. A characteristic feature of my invention consists in providing the cap section arms with angularly disposed tail pieces through which is effected the opening movement of the cap sections after the guard has been moved a predetermined distance away from the closed cap sections and thus completely released the 30 blade from flexing pressure.

These and other features of the invention will be best understood and appreciated from the following description of a preferred embodiment thereof, selected for purposes of illustration and 35 shown in the accompanying drawing, in which:

Fig. 1 is a view in perspective and on an enlarged scale of the razor in closed condition;

Fig. 2 is a view of the razor in vertical cross-section;

Fig. 3 is a plan view of the razor head in open condition, with portions broken away;

Fig. 4 is a view of the razor head in vertical cross-section showing the cap sections closed and the guard separated therefrom;

Fig. 5 is an end view of the razor head in open condition; and

Fig. 6 is a view of the razor head in vertical cross-section corresponding to Fig. 3.

In the preferred embodiment of the present 55 invention the guard 10 is utilized as a blade-sup-

porting member for flexing the blade and clamping it in shaving position. The guard 10 is constructed of heavy sheet metal and provided along its longitudinal edges with spaced curved guard teeth 11 of the usual construction. The guard is 5 formed by die-pressing or moulding a single piece blank and is provided with notches 12 adjacent to each corner, centrally disposed notches 13 in each end and a centrally threaded stem 14. It is also provided with a pair of diamond-shaped apertures for the reception of guide pins 18 of similar shape which project upwardly from the handle member.

The threaded stem 14 is received within an internal threaded cylindrical nut 15 and the nut is 15 received within an opening in the handle member 16 and journaled at its lower end upon a cylindrical boss 17 formed from the material of the handle member and extending upwardly into the opening for the nut. The upper end of the opening in the handle member 16 has portions which project above the end of the nut 15 and with which the nut reacts when turned to lower the threaded stem 14 and the guard 10.

The handle member 16 is provided with outwardly extending brackets 19 to which are rigidly secured the transverse arms 20 which lie beyond the ends of the movable guard 10. Co-operating cap sections 21 are pivotally mounted upon the ends of the transverse arms 20 by means of arms 30 22 which extend vertically and downwardly when the cap sections are closed, as shown in Figs. 2 and 4, and horizontally and inwardly when the cap sections are opened, as shown in Figs. 3 and 5. Each of the arms 22 is provided with an inwardly extending tail piece 23 each being disposed at about 90° with respect to its associated arm 22.

It will be seen that the central notches 13 of the guard register with the brackets 19 of the handle member and that the corner notches 12 fit about the cap section arms 22 when the latter are vertically disposed in closed cap position. Thus the guard 10 is effective to lock the cap sections positively in closed position except when the guard is moved downwardly to its lowermost 45 position, as shown in Fig. 5. Under these conditions the pivot points of connection between the arms 22 and the transverse arms 20 are located above the surface of the guard, so that the cap sections may be swung downwardly as shown in 50 Fig. 5.

The blade 24 employed with the razor above described is provided with corner notches which clear the arms 22 of the cap sections and with diamond-shaped openings fitting the guide pins 55

18. The corner notches define elongated centrally disposed end portions which project beyond the ends of the cap sections.

Assuming that the nut 15 has been turned to 5 elevate the guard 10 into blade-flexing position, as shown in Fig. 2 and that the user desires to open the cap sections for replacing the blade or cleaning the razor, he has then only to turn the nut 15 toward the left, as seen in Fig. 2, whereupon the 10 nut, reacting against the projecting portions of the handle 16, will move the guard 10 vertically downwardly into the position shown in Fig. 4, meanwhile maintaining the cap sections locked in closed position. When the guard 10 reaches 15 the position shown in Fig. 4 further movement of the nut in the same direction will further lower the guard 10 causing it simultaneously to engage the tail piece 23 of the cap section arms and to swing the cap sections outwardly into the position shown in Fig. 5, the arms 22 meanwhile passing upwardly and out of the notches 12 of the guard, thus unlocking the cap sections and leaving them free for pivotal movement. The blade 24 is now fully exposed for removal, and may be 20 conveniently replaced if desired. When it is again desired to close the razor upon the blade the nut 15 is turned in the opposite direction whereupon the shoulders of the guard 10 adjacent to the notch 12 engage the underside of the cap 25 section arms 22 and swing upwardly the arms with the cap sections into closed position as shown in Fig. 4. The cap sections are thus again locked in closed position and further upward movement of the guard to effect the blade-flexing 30 operation ensues with the cap sections locked in position.

It will be noted that the effective length of the tail pieces 23 is much shorter than that of the cap section arms 22 so that a relatively short movement of the tail pieces under the actuation of the guard 10 causes a greatly increased and faster movement of the cap sections. This construction, therefore, is of particular advantage and securing a light acting and quick moving safety 45 razor, characteristics much appreciated by the user.

Having thus described my invention what I claim as new and desire to secure by Letters Patent is:—

50. 1. A safety razor having, in combination, a

handle having outwardly extending brackets, a cross arm secured to each bracket, cap sections pivotally mounted at the outer ends of the cross arms, and a guard movably mounted in the razor and connected with the cap sections so as to swing them toward or from each other in its movement. 5

2. A safety razor having, in combination, pivotally mounted cap sections having downwardly extending arms which are vertically disposed when the cap sections are closed, and a guard apertured 10 to receive said arms and arranged to be moved vertically a predetermined distance without affecting the position of the sections and then to swing them into open position in its further movement. 15

3. A safety razor having, in combination, pivotally mounted cap sections having arms which are substantially vertically disposed when the cap sections are closed, a guard apertured to receive said arms and to move up and down thereon for 20 a predetermined distance to clamp or unclamp a blade without affecting said cap sections, and means operative to swing the cap sections at the conclusion of such predetermined movement of the guard. 25

4. A safety razor having, in combination, pivotally mounted cap sections having downwardly extending arms, a guard apertured to receive said arms, and an angular projection on each arm adapted to be engaged by the guard after it has 30 made a predetermined movement out of blade clamping position.

5. A safety razor having, in combination, a support, cap sections with downwardly extending arms pivoted to the support, a guard with apertures spaced to lock said arms in vertical position with the cap sections positively closed, and means for moving the guard to carry it below the pivot points of the arms and so unlock them for separating movement. 35

6. A safety razor having, in combination, a support, cap sections pivotally mounted on said support and, when in open position, having inwardly extending arms each provided with an angular tail-piece, and a movable blade-supporting plate 45 having notches for receiving said arms, swinging them inwardly, locking them in closed cap-section position, and also bringing said tail-pieces into operative relation with said plate. 40
